[57] CLAIM

The ornamental design for a hair control piece, as shown and described.

DESCRIPTION

FIG. 1 is a perspective view of a hair control piece showing my new design as worn. The broken line showing of a person's head being for illustrative purposes only and forming no part of the claimed design;

FIG. 2 is a right side elevational view;

FIG. 3 is a top plan view;

FIG. 4 is a front elevational view;

FIG. 5 is a rear elevational view; and,

FIG. 6 is a bottom plan view.

The left side elevational view is a mirror image of the right side elevational view.
